UNITED STATES PATENT OFFICE.

GEORGES CLOETENS, OF BRUSSELS, BELGIUM, ASSIGNOR OF ONE-THIRD TO GEORGES LALOUX, OF LIEGE, BELGIUM, AND ONE-THIRD TO LOUIS VAN DER HEYDEN A HAUZEUR, OF BRUSSELS, BELGIUM.

STRINGED MUSICAL INSTRUMENT.

1,392,245.

Specification of Letters Patent. Patented Sept. 27, 1921.

Original application filed January 19, 1920, Serial No. 352,345. Divided and this application filed March 7, 1921. Serial No. 450,496.

To all whom it may concern:

Be it known that I, GEORGES CLOETENS, manufacturer of organs at Brussels, Belgium, 37 Rue de Lauzanne, a subject of the King of Belgium, have invented certain new and useful Improvements in Stringed Musical Instruments; and I do hereby declare the following to be a full, clear, and exact description of the invention, such as will 10 enable others skilled in the art to which it appertains to make and use the same, reference being had to the accompanying drawings, and to letters or figures of reference marked therein, which form a part of this 15 specification.

This invention relates to stringed musical instruments played by key-board, such as pianos, harpsichords, etc., or by the fingers, like the harp, being a division of an application, entitled "Stringed musical instruments," filed January 19, 1920, Serial No. 352,345.

The object of the invention is to provide means for modifying the sounds produced 25 by the strings to produce the effects of strings which are plucked, *i. e.*, effects similar to pizzicato.

The above result is attained according to the present invention by providing presser 30 means positioned to be brought to press firmly upon the strings near the ends thereof to shorten the duration of the sounds.

In the accompanying drawings, which illustrate, by way of example, some constructional forms of the invention,—

Figure 1 is a partly diagrammatic view of the general arrangement of the strings of a piano and of a portion of the apparatus constituting the invention;

Fig. 2 is a fragmentary sectional view of Fig. 1 at right angles to the strings;

Figs. 3 and 4 are fragmentary sectional views on the lines 3—3 and 4—4 of Fig. 2, respectively; and

Figs. 5, 6 and 7 are fragmentary sectional views similar to Fig. 3, and illustrating three other constructional forms.

The strings 3 are stretched in the usual way over the plate 1, 2. They are operated 50 in the usual way by hammers (not shown) acting at a certain distance from the front part 1 of the plate.

The apparatus constituting the present in-

vention comprises in all the various modifications illustrated, except that illustrated 55 in Fig. 7, a supporting bar 4 positioned above the strings and extending transversely of the length thereof and near their ends, as shown in Fig. 1.

The construction illustrated in Figs. 2 60 and 3 comprises a bar 5 supported beneath the bar 4 in spaced relation thereto by means of screws 6. For constructional reasons the bar 5 may be divided longitudinally into a number of sections. The bar 5 carries presser means for the strings of each note (each note may be produced by a triple string 3' as illustrated in Fig. 2) comprising a disk 8 covered with felt and secured to the end of a screw-threaded rod 7 extending vertically through the bar 5 in screw-threaded engagement therewith. These screw-threaded rods permit of the exact adjustment of the position of the members 8 with respect to the strings. 75

Overlying the supporting bar 4 adjacent one end thereof is a wedge member 9 which coacts with an inclined face on the bar. The wedge member 9 is actuated through a rod 10 provided with a handle member 80 near the key-board. Actuation of the wedge member 9 by means of the rod 10 causes the supporting bar 4 to be depressed, thereby bringing the pressers 8 firmly into contact with the strings. Return of the 85 supporting bar 4, and the parts carried thereby, to normal position is effected by the tension spring 11.

In the case where each note has three strings (as illustrated in Fig. 2), to cause 90 each presser 8 to touch only two strings, or only a single string, the support 4 must be moved longitudinally and this is effected by means of the wedge 12 (shown in Figs. 1, 2 and 4) which engages the inclined end of 95 the support and is actuated through the medium of a rod 13. The return of the support 4 to normal position is effected by spring 14 (shown in Fig. 2).

It will be understood that the end of the 100 supporting bar 4 opposite that engaged by the wedges 9 and 12 will be supported by suitable means permitting the movements of the support caused by the wedges.

In the constructional form shown in Fig. 105 5, bar 4 carries by means of screws 6 a bar

5' similar to the bar 5 of Figs. 2 and 3. Instead of the bar, however, carrying a separate presser for the strings of each note, it carries along the whole of its length 5 a projecting pad formed by a string 19 covered with felt 20.

In the construction shown in Fig. 6, bar 4 carries a bar 5" similar to the bar 5 of Figs. 2 and 3. The bar 5" has along the 10 whole of its length on its under side a groove 21 which is closed by a diaphragm 22 which may be kept inflated by air pressure or the like.

It is obvious that in the constructions 15 shown in Figs. 5 and 6 the means for shifting bar 4 longitudinally will be omitted. It will be obvious, also, that with the construction shown in Fig. 6 the pizzicato effect will not be as pronounced as with the 20 construction shown in Figs. 2 and 3, due to the resilient nature of the presser means.

In the construction shown in Fig. 7, the support for the pressers is in the form of a bar 15 adapted to rock about on axis 16 25 under the action of an operating rod 18. This bar carries fingers 17 on the free ends of which are fixed the pressers 8 with their screw-threaded rods 7. This construction permits of the exact adjustment of the position of the pressers 8 in the direction of the length of the strings, by moving the 30 fingers 17 relatively to the bar 15, the fixing of these fingers 17 by means of the screws 23 only taking place when the adjustment is finished.

In order to obtain the simultaneous production of several sounds, separate pressers for each string of the same note may also be employed in the construction shown in Fig. 40 7. Each presser 8 is then carried by a separate finger 17 which is movable relatively

to the bar 15, and one or more of these fingers may be raised by means of a suitable device for the purpose of preventing the corresponding presser from coming into 45 contact with the string when the bar 15 is operated.

It is obvious that the support 4 or 15 might also be divided into separate sections 50 operated separately.

Having now specifically described my invention in various of its embodiments, what I claim is:

1. A stringed musical instrument, comprising presser means located to be applied 55 against the strings near the ends thereof, a support for said presser means extending transversely of the length of the said strings, and means for moving said support toward said strings.

2. A stringed musical instrument, comprising a plurality of pressers located to be applied against the strings near the ends thereof, a support common to said pressers, and means for moving said support toward 60 said strings.

3. A stringed musical instrument, comprising a plurality of pressers located to be applied against the strings near the ends thereof, a support common to said pressers, 70 means for moving said support toward said strings, and means for moving said support longitudinally in order that the pressers may be applied only against certain of the strings of each note when the support is 75 moved toward said strings.

In testimony whereof I affix my signature in presence of two witnesses.

GEORGES CLOETENS.
